UNITED STATES PATENT OFFICE.

JOSEPH A. STEINMETZ, OF PHILADELPHIA, PENNSYLVANIA.

METHOD AND MEANS FOR DESTROYING SUBMARINES.

1,325,541.

Specification of Letters Patent. Patented Dec. 23, 1919.

Application filed September 15, 1917. Serial No. 191,636.

To all whom it may concern:

Be it known that I, JOSEPH A. STEINMETZ, a citizen of the United States, and resident of Philadelphia, in the county of Philadelphia and State of Pennsylvania, have invented certain new and useful Improvements in Methods and Means for Destroying Submarines, of which the following is a specification, reference being had therein

10 to the accompanying drawing.

The object of this invention is to provide for the destruction of submarines by small ship's boats. At the present time it is usual for submarines to compel those on an attacked ship, either before or after the ship has been torpedoed, to send to the submarine a small boat with officers and the ship's papers. Except where the ship is allowed to proceed in the interest of the country to 20 which the submarine belongs, those in the small boat are, at best, turned adrift to reach land or a friendly ship as best they may. This invention provides such small boat with concealed means whereby, when 25 very near the submarine, ostensibly to deliver papers and orally answer questions, it may suddenly discharge below the water line and against the side of the submarine a small bomb or torpedo carrying enough 30 high explosive to sink the submarine.

In the accompanying diagrammatic drawings,

Figure 1 shows a ship's small boat approaching a submarine.

35 Fig. 2 is a side view of the small boat, partly in vertical axial section.

Fig. 3 is a cross section of the small boat.

Fig. 4 shows in larger view a simple torpedo or bomb which may be used.

40 In these figures, 5 represents a submarine, 6 a ship attacked thereby, 7 one of the ship's small boats having the ordinary general appearance. Along the keel of the boat is a receptacle 8 for a compressed gas tank 9 45 of cylindrical form, and alining with this receptacle is a tube 10 for containing a torpedo 11 preferably provided with suitable encircling rings 12 to secure a close fit in the tube. The rear end of the tube has a 50 sort of removable breech block 13, through which a pipe 14 discharges. The pipe 14 communicates with the interior of the tank through a valved pipe 15 detachably connected to the pipe 14 by a suitable coupling 55 16, without novelty, and the forward end of the tube 10 may be closed in any suitable

way, as by a spring-closed flap-valve 17 openable by any suitable means, for example a tension wire 18, and ordinarily closed only for placing a torpedo in the tube when 60 the boat is in the water. For putting the torpedo in place, the valve 17 is closed (if open), the coupling 16 is detached, the breech is opened, and the tank is removed if in place.

65 The torpedo is then provided with a war head, or device 19, for detonating by contact and is pushed forward in the tube until the peripheral portion of its rounded end rests against one or another of suitable stops 70 20, any of which may be withdrawn by those in the boat, as shown, by pressing upon a centrally pivoted lever 21 connected with the corresponding pin stop 20. The torpedo being in place, the breech block is 75 inserted, the tank is adjusted in place, and the pipes 14, 15 are coupled. At the proper time the valved pipe 15 is opened allowing the highly compressed gas to pass into the tube in the rear of the torpedo, which is 80 thereby urged forward with a force depending on the initial pressure in the tank and the relative volume of the space in the same and in the tube. The tube space mentioned depends upon the distance to which the 85 torpedo is initially advanced in the tube, and as the pressure in steel tanks may safely be very high, this pressure is easily made ample for driving the torpedo through many times the distance probably necessary for 90 effective use. Preferably the volume in the rear of the torpedo will be large enough to exert high propelling force up to the time when the torpedo leaves the tube.

95 The torpedo being in place, the valve 17 is opened (if closed) and the valve controlling the tank discharge is opened. When the torpedo is to be ejected the proper lever 21 is suddenly depressed withdrawing its stop 20, whereupon the torpedo is suddenly 100 shot forward and an instant later is exploded against the submarine which the boat has closely approached. There is no time for defense or counter-attack.

105 The firing tube may be loaded before the boat is launched and without breaking the high pressure connection or opening the breech block, by the simple expedient of opening the forward valve 17 and inserting the projectile as in muzzle loaders. By this 110 means, exposing the ammunition and suspicious movements in the boat are avoided,

discharge of the projectile being secured by mere pressure of the foot in a boat apparently of usual construction, containing nothing for attack, and being operated in the usual way.

5 What I claim is:

1. The method of destroying submarines which consists in providing a ship's small boat with torpedo discharging devices the presence of which is not suggested to the eye of the ordinary observer by the form of the boat or otherwise, and with devices whereby an occupant of the boat may by movements not suggesting hostility cause
- 10 the discharge of a torpedo by said devices for discharging.
- 15 2. The combination with a ship's small

boat internally and externally of ordinary general appearance, of a torpedo-discharging tube carried by the boat and invisible 20 to ordinary observers, and means whereby an occupant of the boat may at will and without unusual movements cause the discharge of a torpedo from said tube.

3. The combination with a ship's small 25 boat of ordinary general appearance having along its keel a concealed torpedo tube, of a tank for compressed gas, and operator-controlled means for supplying to the tube gas from the tank to expel, secretly, a torpedo therefrom.

20 In testimony whereof I hereunto affix my signature.

JOSEPH A. STEINMETZ.
